UNITED STATES PATENT OFFICE

BERNHARD REDDEMANN, OF BERLIN-LICHTERFELDE, GERMANY, ASSIGNOR TO
PYRENE-MINIMAX CORPORATION, A CORPORATION OF DELAWARE

SPRINKLER FOR DISTRIBUTING FOAM FOR FIRE-EXTINGUISHING PURPOSES

Application filed August 31, 1927, Serial No. 216,663, and in Germany September 1, 1926.

My invention relates to a sprinkler for distributing foam for fire extinguishing purposes, and more particularly to such a device in which the foam dropping down from above is accurately confined to a definite width on 5 the ground below. Such a restricted spraying of the foam upon the floor may, for instance, become necessary in connection with sprinkler located above gangways or alleys between rows of transformers or oil switches 10 in electric power plants.

According to my invention the sprinkler is provided with deflecting or baffle plates, which are, for example, pivoted upon a collar or strap surrounding the foam delivery 15 pipe and which may thus be adjusted under any suitable angle to the sprinkler. The foam squirted uniformly towards all sides by the sprinkler is at the places where it encounters the baffle plates deflected from the direction in which it is projected so that it covers 20 on the floor a comparatively long but narrow area, the width of which may be varied at will.

25 The drawing affixed hereto illustrates an embodiment of my invention.

Referring to the single figure of the drawing, *a* is a fire foam pipe descending from the ceiling from which the foam is conducted 30 through the webs *c* on to a distributor plate *f*, so that it passes along in the direction of the arrows. Upon the lower end of the pipe *a* is mounted a collar or strap *b* which carries pins *d* upon which baffle or deflecting 35 plates *e* of suitable size are pivoted. As clearly shown in the drawing these plates *e* may be adjusted under any desired angle to the axis of the pipe *e*. They may be fixed in the adjusted position by winged nuts or 40 the like screwed upon the pins *b*. The foam is conducted against the floor of the room to be protected in the direction of the arrows shown in the lower part of the drawing.

Various changes and modifications may be 45 made without departing from the spirit of my invention and the appended claim should be interpreted in the light of the prior knowledge.

I claim as my invention:—
50 In a sprinkler device for fire foam, in

combination, a descending foam supply pipe, a horizontal baffle plate supported by said supply pipe in spaced relation thereto but in the path of the stream of foam issuing from the end of said pipe to direct the foam laterally in the opposite directions, a rotatable collar mounted upon the lower end of said pipe, pivot pins fixed upon said collar, baffle plates pivoted upon said pins and extending laterally of the horizontal baffle plate and 55 across the paths of the foam as deflected by said horizontal baffle plate, and means for locking said plates in any angular position to the axis of said foam delivery pipe.

DR. BERNHARD REDDEMANN.
